234,301

ELECTRONIC DISPLAY UNIT FOR A CASH REGISTER OR SIMILAR ARTICLE

Lynton Randolph Knapp, Orange, and Ralph Waldo
Province, Westminster, Calif., assignors to MSI Data
Corporation, Costa Mesa, Calif.

Filed Feb. 10, 1972, Ser. No. 225,364

Term of patent 14 years

Int. Cl. D14—02

U.S. Cl. D26—5 C

FIG. 1

FIG. 2

FIG. 3

FIG. 4

FIG. 1 is a front elevational view of an electronic display unit for a cash register or similar article showing our new design;

FIG. 2 is a top plan view thereof;

FIG. 3 is a rear elevational view thereof;

FIG. 4 is a right side elevational view thereof, the bottom being plain and unornamented.

The bottom side of the electronic display unit for a cash register or the like is plain and unornamented.

We claim:

The ornamental design for an electronic display unit for a cash register or similar article, as shown and described.
